ENTOMOLOGICAL OBSERVATION DEVICE

Stanley S. Sheidlower, 43 Burton Ave., Woodmere, N.Y.
11598, and Elliot S. Glanz, 4005 Greentree Drive,
Oceanside, N.Y. 11572

Filed June 11, 1970, Ser. No. 23,444

Term of patent 14 years

Int. Cl. D19—08

U.S. Cl. D25—1

Fig. 1.

Fig. 2.

Fig. 3.

FIG. 5.

FIG. 6.

FIG. 4.

FIG. 7.

FIG. 1 is a front and top isometric view of the entomological observation device, embodying the features of our new design.

FIG. 2 is a rear elevation view,

FIG. 3 is a side elevation view,

FIG. 4 is a top perspective view of another embodiment of the design wherein the A-frame top and the slot therein have been omitted and a planar top has been employed.

FIG. 5 is a rear elevational view of FIG. 4.

FIG. 6 is a side elevational view thereof.

FIG. 7 is a top perspective view of another embodiment of the design wherein a clamp fits over the center of the planar top.

We claim:

The ornamental design for an entomological observation device, substantially as shown and described.
